DESIGN FOR A NIGHTGOWN

Charles Zinaman, New York, N. Y.

Application June 16, 1943, Serial No. 110,466

Term of patent 3½ years

To all whom it may concern:

Be it known that I, Charles Zinaman, a citizen of the United States of America, residing in New York city, county of New York, and State of New York, have invented a new, original, and ornamental Design for a Nightgown, of which the following is a specification, reference being had to the accompanying drawing, forming part thereof, wherein

I claim:

The ornamental design for a nightgown, substantially as shown.

CHARLES ZINAMAN.
